Inventor

UNITED STATES PATENT OFFICE.

FREDERICK AUBREY KILBOURN, OF CALGARY, ALBERTA, CANADA.

SHOW CASE.

Application filed January 2, 1923. Serial No. 610,350.

My invention relates to improvements in show cases, the object of which is to provide a means of utilizing the whole of the wall space of a store, from the floor to the ceiling, for displaying goods and holding stock. With my invention it is possible to have stocks of goods concealed and brought to the desired position whenever desired, for either sale or display, and the advantage of not having to leave a customer to find goods stored in a basement or upon a high shelf will be obvious.

In the accompanying drawings it is sought to illustrate how this may be accomplished, using one of the many means available for this purpose.

Fig. 1, is a vertical section showing the sales floor and the room below in which the raising and lowering mechanism is installed, it also shows the show case and the balancing means. Fig. 2, is a front view showing fragmentary portions of the show cases on the sales floor. Fig. 3, is an enlarged horizontal cross section showing the guide rail and wheels traversing the said rail. Fig. 4, is an enlarged vertical elevation of a portion of the rail and show case units, showing particularly the guide wheels in relation to the show case units and rails.

Similar characters refer to similar parts throughout the several views.

The show cases *a*, are of a height approximating that of the store from floor to ceiling, and as, in the most stores this height

would make the goods in the uppermost portion of the case inaccessible, the show cases are suspended in units and may be lowered through the floor *h*, into the room below. For this purposes cables *b*, are connected to the tops of the units *a*, which cables pass over pulleys *c*, and have balance weights *d*, attached to their ends. Rails *e*, are provided to guide the show cases, which rails extend from the ceiling of the store to the floor of the room below, suitable rollers *f*, being mounted at intervals upon the show case units *a*, to traverse the said guide rails. Each show case unit is provided with a suitable, controlled lifting unit *g*, which device raises or lowers the show case unit *a*, to the desired position for the display of goods or stock. Any portion of the show case unit may therefore be brought to a convenient position. A screen *i*, is provided to conceal the cables *b*, and the pulleys *c*, which screen is hung from the ceiling of the store.

What I claim is:

A sectional vertically extending merchandise holder having shelves therein, said holder being of sufficient height to extend from the floor to approximately the ceiling of a salesroom and means for independently and bodily lowering each section of said holder through the floor of the room in which it is placed so as to place the normally inaccessible shelves in the upper parts of the holder within convenient reach.

FREDERICK AUBREY KILBOURN.
